BOX MARKING APPLIANCE

Roy V. Waughtel and Ray A. McDermont,
Riverside, Calif.

Application July 10, 1933, Serial No. 679,670

5 Claims. (Cl. 101—35)

This invention relates generally to appliances for the marking of boxes, crates or the like, with numbers or like designating characters for future identification. Appliances of this character are particularly useful in packing houses or other plants where various articles are being packed in boxes or crates for distribution to the trade.

It is an object of the invention to provide an appliance of the above character which will be relatively simple in construction and convenient to operate.

A further object of the invention is to provide a marking appliance which can be used in conjunction with a conveyor or machine handling boxes or crates, and which can be readily adjusted to secure different kinds of markings which may be required.

Further objects of the invention will appear from the following description in which the preferred embodiment of the invention has been set forth in detail in conjunction with the accompanying drawings.

Referring to the drawings:

Figure 1 is a side elevational view, illustrating 25 a box marking appliance incorporating the present invention.

Fig. 2 is a cross sectional detail taken along the line 2—2 of Fig. 1.

Fig. 3 is a cross sectional detail taken along the 30 line 3—3 of Fig. 1.

Fig. 4 is a cross sectional detail taken along the line 4—4 of Fig. 1.

Fig. 5 is a cross sectional detail taken along the line 5—5 of Fig. 1.

Fig. 6 is a cross sectional detail taken along the line 6—6 of Fig. 5.

Fig. 7 is a plan view illustrating the manner in which our appliance can be applied to a conveyor over which the boxes or crates to be marked are 40 passed.

Referring first to Fig. 1, the appliance consists generally of a supporting standard 10, which can be in the form of a hollow casting. To facilitate attachment of this standard to another structure, such as a conveyor or a box-handling machine, the lower portion of the standard is shown provided with apertured portions 11 for receiving clamping bolts. An upright shaft 12 is disposed within standard 10, and secured to the upper end of this shaft there is a head 13. A second shaft 14 (Fig. 5), which is preferably tubular in form, is journaled within head 13. This second shaft is cantilever-like in that it extends outwardly or laterally with respect to the standard and head

13. Likewise its axis is substantially at right angles to the axis of shaft 12.

Extending thru tubular shaft 14 there is a rod 16, one end of which is provided with a knob 17 to facilitate manual turning of the same. Removably secured to the outer end of rod 16 there is a cylindrical shaped body 18, which carries a printing stamp 19. This stamp can be made of suitable material, such as soft vulcanized rubber, and is provided with a plurality of spaced numbers or letters about its periphery. It is frequently desirable to mark a box with a number, and also with letters or words designating the type of article being packed. Thus removably mounted upon tubular shaft 14, there is a sleeve 21, carrying a separate printing stamp 22.

Detent means is preferably interposed between rod 16 and shaft 14, to retain rod 16 in any one of a number of desired positions depending upon the position desired for stamp 19. Thus sleeve 21 is shown provided with a bore 33 within which a plunger 34 is slidably fitted. Spring 35 urges plunger 34 against one end face of the body 18, which is provided with spaced indentations 36, within which the end of plunger 34 may engage.

Actuation of the appliance is by virtue of turning movement imparted to the shaft 12. While various forms of actuating mechanism can be employed, as for example hand operated levers or the like, the mechanism illustrated in Fig. 1 consists of a pivoted foot lever 37 which can be mounted upon the floor. Journaled within the lower portion of standard 12 there is a shaft 38 extending substantially at right angles to the shaft 12, and this shaft has a drive connection with shaft 12 thru the bevel gears 39 and 41. A crank 42 is fixed to shaft 38, and this crank is connected to the foot lever 37 thru link 43.

Suitable spring means is employed for urging shaft 12 to rotate in one direction, or for urging foot lever 37 towards an elevated released position. Thus surrounding shaft 12 there is a helical spring 44, one end of which is secured to shaft 12, and the other end of which is secured to the standard 10 as indicated at 46 in Fig. 6. When foot lever 37 is depressed shaft 12 is rotated against spring 44 thru an angle of substantially 90 degrees. When the foot lever 37 is released it immediately returns to an elevated position, and shaft 12 rotates back to its initial position under the tension of spring 44.

When foot lever 37 is depressed to rotate shaft 12 thru substantially 90 degrees, it is evident that shaft 14 is swung thru a similar angle so that the printing stamp 19, and also stamp 22, are

swung from a non-printing position to a position in contact with one face of the box to be marked. To facilitate an automatic inking operation, as will be presently explained, it is desirable to 5 cause shaft 14 to rotate about its axis, simultaneously with its swinging movement. Thus mounted upon the upper end of the support standard 10 there is a bevel gear 48, the teeth of which are engaged by the teeth of a bevel 10 pinion 49. This pinion is in turn fixed to shaft 14, so that as this shaft swings about the axis of shaft 12, it is simultaneously rotated.

The means provided to effect automatic inking can be explained by reference to Figs. 2 to 5 inclusive. Mounted upon the upper portion of support standard 10, there is a bracket 51 formed to afford a hood-shaped portion 52. Disposed within the hood-shaped portion 52 there is a roller 53, which is squared or otherwise formed to afford 20 flat sides. The ends of roller 53 carry stud shafts 54 and 56 which are suitably journaled within bracket 51. A knob 57 is secured to the stud shaft 54 for manual turning of the roller. Suitable detent means serves to retain roller 53 in 25 any one of a number of adjusted positions. Thus as shown in Fig. 4, detent means may be formed by a spring finger 58 which presses upon the flattened sides of the roller. The outer surface of the roller 53 is covered with a suitable absorbent pad 59 which can be saturated with ink.

Fig. 7 illustrates the manner in which the appliance can be utilized in conjunction with a conveyor 61. In this case the support standard 10 is secured to one of the side rails 62 of the 35 conveyor, with the foot lever 37 mounted upon the floor or at any other suitable operating position. It will be noted that the arrangement is such that when the foot lever is released shaft 14, together with the printing stamps 19 and 22, 40 is swung to an out of the way position, to one side of the path of movement of boxes along the conveyor.

Operation of our appliance is as follows:—It will be presumed that stamp 19 contains various 45 circumferentially spaced lot numbers and that the letters on stamp 22 designate the type of articles within the boxes. By turning knob 17, the operator adjusts the position of stamp 19, in order to impress the number desired upon the 50 box. In this connection knob 17, together with the adjacent portion of the head 13, can be provided with suitable indicia, to apprise the operator of the position desired. Referring now to Fig. 7, and assuming that a box 64 has been 55 moved to a proper position for marking, the operator forces foot lever 37 downwardly, thus causing shaft 14 to swing over the conveyor towards the end face of the box. At the same time shaft 14 is rotated thru an angle of substantially 180 60 degrees, so that stamp 22 and also the selected number upon stamp 19, which were previously in engagement with the inking pad 59, are brought into proper printing engagement with the box. It is evident in this connection that lever 37 65 should be operated with sufficient force to bring the stamps into contact with the box with proper impact, to insure a good impression. Following the making of an impression upon the box the operator releases foot lever 37, and then shaft 70 14 immediately swings back thru 90 degrees, until the stamps 22 and 19 engage the inking pad 59. The box which has been printed is then permitted to pass along the conveyor, and a new box brought into a printing position. From time 75 to time knob 57 may be rotated to bring a freshly

inked pad surface into contact with the stamps, thus insuring a long period of operation without the necessity of renewing the ink pad.

We claim:

1. In a box marking appliance, a supporting standard, a shaft journaled with respect to said standard, a head secured to one end of said shaft and adapted to rotate therewith, means forming a fixed stop adapted to limit rotation of said shaft in one direction, spring means tending to urge said shaft to rotate in a direction towards said stop, a second shaft having one end portion thereof journaled to said head, said second shaft extending outwardly with respect to the standard substantially at right angles with respect to the axis of the first shaft, a printing stamp carried by the outer end portion of said second shaft, actuating means for rotating said first shaft whereby said second shaft can be swung thru an angle of substantially 90 degrees, and means acting between said second shaft and said support for turning said second shaft simultaneously with swinging movement of the same. 80

2. In a box marking appliance, a support, a shaft journaled with respect to said support, a head secured to one end of said shaft and adapted to rotate therewith, a second tubular shaft having one end portion thereof journaled with respect to said head, said second shaft extending outwardly with respect to said support, a rod extending thru said second mentioned shaft and rotatable with respect thereto, a printing stamp carried by one end of said rod, detent means acting between said second shaft and said rod for retaining the rod in any one of a number of adjusted positions with respect to said second shaft, actuating means for effecting rotation of said first shaft whereby the second shaft is swung through an angle of at least 90 degrees, and means acting between said second shaft and said support for effecting rotation of said second shaft simultaneously with said swinging movements. 100

3. In a box marking appliance, an upright supporting standard, a head disposed upon the upper end of said standard, a shaft journaled within said standard and having its upper end secured to said head, stop means serving to limit rotation of said shaft in one direction, spring means for urging said shaft to rotate in the direction of said stop, actuating means for rotating said shaft 110 in a direction away from said stop, a second tubular shaft having one end portion thereof journaled to said head, said second shaft extending laterally from said head cantilever-like, a rod extending thru said second shaft and rotatable 115 with respect thereto, a printing stamp secured to one end of said rod adjacent the outer end of said second shaft, means for manually rotating said second shaft, detent means acting between said second shaft and said rod serving to retain said 120 rod in any one of a number of adjusted positions with respect to said second shaft, a second printing stamp mounted upon the outer end portion of said second tubular shaft, and means acting between said second shaft and said standard for 125 causing rotation of said second shaft about its axis upon rotation of said first shaft. 130

4. In a box marking appliance, a supporting standard, a shaft journaled to said standard, a head secured to one end of said shaft, a second shaft having one end portion thereof journaled to said head, said second shaft extending outwardly cantilever-like with respect to said standard and being substantially at right angles with respect to the axis of the first shaft, a printing 145 150

- stamp carried by the outer end portion of said second shaft, actuating means for rotating said first shaft whereby said second shaft is caused to swing about the axis of the first shaft, spring means urging said first shaft to rotate in one direction, a bracket secured to said standard and extending outwardly therefrom, a roller secured to said bracket and capable of angular adjustment, a printing pad secured to the outer surface 5 of the roller and adapted to be engaged by said stamp, and means acting between said second shaft and said standard for rotating the second shaft simultaneously with swinging movement thereof.
- 10 5. In a box marking appliance, a supporting standard, a shaft journaled with respect to said standard, a head fixed to one end of said shaft, a second shaft having one end portion thereof journaled with respect to said head, said second shaft extending outwardly from said standard substantially at right angles to the axis of said first shaft, cantilever like, a printing stamp carried by the second shaft, means acting between said second shaft and said standard serving to cause rotation of said second shaft simultaneously with rotation of said first shaft to swing the second shaft, a bracket extending outwardly from said standard, an inking pad carried by said bracket and adapted to be engaged by said printing stamp, and means for normally biasing said first shaft to rotate in a direction to urge the printing stamp into engagement with the inking pad.
